APPARATUS FOR SELECTIVE VERBATIM CODING AND DECODING

Original Filed June 25, 1925 2 Sheets-Sheet 2

UNITED STATES PATENT OFFICE

HARRY R. BARNETT, OF DENVER, COLORADO

APPARATUS FOR SELECTIVE VERBATIM CODING AND DECODING

Application filed June 25, 1925, Serial No. 39,577. Renewed July 30, 1929.

My invention relates to a new apparatus for selective verbatim coding and decoding or translating a given vocabulary for telegrams, cablegrams and radiograms.

5 And the objects of my invention are:

First: To provide a new apparatus for selection or formation and combination at will of letters, words, groups of words, phrases, parts of phrases, or sentences, figures and 10 characters, comprising a given vocabulary, and the consequent formation and combination of coding words necessary for the transmission of same via telegraph, cable or radio, commonly known as telegrams, cablegrams 15 and radiograms; the apparatus particularly affording brevity and secrecy in transmission; likewise the decoding or translation of same by the recipient by reversing the coding operation.

Second: To provide a new apparatus for 20 coding and decoding telegrams, cablegrams and radiograms that is co-operatively combined with a mechanical apparatus provided with strips of initial letters and sentence-forming words and phrases for directing the 25 selection of the coding and decoding letters and words so co-operatively arranged that telegrams, cablegrams and radiograms comprised of sentences may be coded from the 30 letters of the alphabet on the said strips and may also be decoded or translated in reverse manner by the recipients of telegrams, cablegrams or radiograms, using the same system and apparatus.

Third: To provide a new type and character of telegram, cablegram and radiogram-transmitting words, letters, figures and characters, also tables and specifications dimensions, prices, percentages, distances, weights, measures, quantities, numerals and other valuable information, arranged on rollers in a cabinet so arranged that the sender of telegrams, cablegrams or radiograms may select 40 initial letters, words and phrases at will and

in very much less time than by the coding and decoding systems now in use.

Fourth: To provide a telegram, cablegram and radiogram coding and decoding apparatus; comprising strips of any suitable material having columns of words and phrases and indicating code letters for said words and phrases printed or otherwise placed on them in connection with mechanism for shifting said strips in the selection of combinations 55 of one or more letters, syllables, words, groups of words, figures, characters or tables, phrase or part of a phrase, one or more sentences, or part of a sentence with one or more letters, syllables, words, groups of 60 words, figures, characters, or tables, phrase or part of a phrase, one or more sentences, or part of a sentence as may be necessary for the proper expression of thought, the system being used either with or without the 65 strip shifting mechanism.

I attain these objects by the mechanism illustrated in the accompanying drawings and described in the accompanying specification in which:

Fig. 1, is a perspective view of a cabinet provided with a strip having five columns of words or phrases printed thereon, said strips being connected at its ends to rollers so as to be moved in either direction.

Fig. 2, is a transverse sectional view through the cabinet on the line 2—2 of Fig. 3, showing the rollers to which the ends of the code strip are attached, and the gearing by which the rollers are turned simultaneously and in the same direction.

Fig. 3, is a plan view of one end portion of the cabinet showing the rollers and their operating gears.

Fig. 4, is a plan view illustrating a modified form of the coding apparatus, in which three independent code strips are employed, which are attached to three pairs of independently operated rollers.

Fig. 5, is an end view of Fig. 4.

Fig. 6, in a transverse sectional view thereof on the line 6—6 of Fig. 4.

Fig. 7, is a transverse sectional view through one of the rollers, showing the manner of connecting one end of the code strip thereto.

Fig. 8, is a sectional view through a portion of the cover of the cabinet, showing a glass panel over the opening through which 10 the code phrases are displayed.

Fig. 9, is a perspective view of one end portion of the plate which supports the code strip relatively to the opening in the cover.

Referring to Figures 1, 2 and 3 of the drawings: The letter A indicates a cabinet which 15 may be of any required dimensions; and which comprises an oblong housing, having a removable cover 2. The front side 3 of the cabinet is preferably of less height than the 20 rear side, and the ends of the cabinet are the same height as the rear side thereof for a short distance from the said rear side and then incline downward to the front side as shown. The cover 2, is bent longitudinally 25 to conform to the outline of the upper edges of the said ends, and the front and end edges of said cover are bent down to form a lip 4, which overlies the edges of the front side and the ends of the housing. The rear edge 30 of the cover is slid beneath a longitudinal rod 5 which is secured to the upper edge of the rear side of the housing and a spring latch 6 is secured to the under side of the cover adjacent its front edge, and is adapted to engage 35 the upper edge 7 of the front side of the housing, which is bent over at an angle for that purpose, as shown in Fig. 2. Thus, the cover can be quickly attached to the housing, or removed therefrom when necessary.

40 A longitudinal slot or sight opening 8, is formed in the inclined portion of the cover through which the words, phrases, code letters and numbers on the code strip are seen, and in selecting the required words and 45 phrases to make up a given message, the code strip is shifted to bring the required word or phrase to stand just above the lower edge of the opening, thus shutting out all words or phrases below the line in which the desired word or phrase occurs and thereby 50 eliminating the possibility of selecting the wrong word or phrase.

A longitudinal plate 9, of slightly greater width than the opening 8, is positioned below 55 the said opening, and separated from the cover by a slight space. The longitudinal edge portions of this plate are bent over at right angles, as shown at 9A in Figures 2 and 9 to give rigidity to the plate, and the 60 ends of the plate extend slightly beyond its bent side edge, as shown at 9B, and these extending portions rest in recesses 9D which are formed in the upper edges of the ends of the housing.

65 Rollers 10 and 11 are mounted in the hous-

ing and these rollers have metal disks 12 secured upon their ends in any suitable manner, which confine the code strip upon the rollers and guide it as it unwinds from one roller and is wound upon the other roller, and 70 these disks are provided with short trunnions 13 which are mounted in bearing holes in the ends of the housing. The trunnions at the right hand ends of the rollers are provided with pinions 14 which mesh with a relatively large gear wheel 15 which is loosely 75 mounted on a rod 16 which is secured at its ends to the ends of the housing. A small axial pinion 17 is secured to the gear 15 and a driving gear 18 of about twice the diameter 80 of the pinion 17, meshes with the said pinion 17 and is secured upon a short stem 18B, which is mounted in a hub on the adjacent end of the housing, and a knob 19 is secured upon the outer end of the stem. The gear 15 turns both of the pinions 14 in the same direction, and one rotation of the driving gear 18 causes two rotations of the gear 15 and about four rotations of the rollers, whereby 85 the code strip is rapidly unwound from one roller and wound upon the other roller. Although the angular velocities of the rollers 10 and 11 will vary as the strip passes from one roller to the other, I have found that no difficulties are encountered from this change 90 in angular velocities when the strips are comparatively short, and with longer strips any of the known or appropriate over-run clutches (not shown) may be included in the driving mechanism. The rollers 10 and 11 are provided with longitudinal grooves 20, and one end of the code strip is placed in one of the grooves and the other end thereof placed in the other groove, and square metal 95 rods 21, are forced into the grooves and thus 100 clamp the ends of the strip to the rollers, as 105 will be understood by reference to Fig. 7.

In Figures 1 and 2, I have shown a movable pointer 22 for locating the columns of code letters which indicate the lines of words or 110 phrases. The pointer is secured to a slide 23 having beveled edges, and which is slidably mounted in a groove 24, formed in a metal strip 25, which is secured to the cover 2. The marginal edges of the groove 24 are beveled 115 to correspond to the beveled edges of the slide 23, the groove being wider at the bottom than at the top, so that when the slide 23 is placed therein, it cannot become disconnected from the groove.

The character of code strip used in connection with the cabinet above described will be hereinafter particularly described, and the strip passes from one roller, over the plate 9 120 to the other roller, the plate 9 supporting the exposed portion of the strip in a plane close to the under side of the cover and with relation to the sight opening 8, so that the matter 125 on the strip may be readily seen through the 130

sight opening, as the strip is shifted back and forth in making the phrase selections.

If desired, the sight opening 8 may be and preferably is covered with a glass panel 8B which is secured in parallel cleats 8C as shown in Fig. 8.

In Figures 4, 5 and 6, I show a cabinet which is used in connection with a coding and decoding system employing three code strips, 10 and therefore this cabinet is provided with three pairs of rollers and three independent gear mechanism for operating the three pairs of rollers. The gearing for each pair of outer rollers is identical with the gearing 15 above described, excepting that the driving gear 18, on the right hand end of the cabinet, is shifted to the left of the position shown in Fig. 2, in order to permit two knobs to be used on this end of the cabinet, and the 20 corresponding gear 18 on the left hand end of the cabinet is placed in line with the gear 18 on the right hand end, for the sake of symmetry.

The cabinet is divided by two partitions 25 26 and 27 into three compartments of equal size. The left hand pair of rollers 28 and 29 are mounted in the left end of the cabinet and in the adjacent partition 26; the right hand pair of rollers 32 and 33 are mounted in 30 the right hand end of the cabinet and in the partition 27, and the middle pair of rollers 30 and 31, is mounted in the partitions 26 and 27. The pinions 14 on the middle rollers and the gear wheel 15 which meshes with them, 35 are identical with the corresponding gears and pinions on the rollers 10 and 11 of Fig. 3, but instead of the pinion 17, I employ a pinion 17A of twice the diameter of the pinion 17 and instead of the driving gear 18, I 40 employ a gear 18A of twice the diameter of the pinion 17A, the ratio between the wheels 17A and 18A being the same as between the wheels 17 and 18. The reason for employing the larger wheels 17A and 18A in connection 45 with the middle pair rollers, is to enable the wheel 18A to be operated from the right hand end of the cabinet, by a rod on shaft 34 which must be positioned outside the path of the large gear 15, as will be understood by reference to Fig. 6. The rod 34 to which the said gear wheel 18A is rigidly secured, is mounted at its inner ends in the partition 26, and passes loosely through the partition 27, and through the right hand end 50 of the cabinet and upon its outer end is secured an operating knob 35, the driving gear 18 of the right hand pair of rollers being operated by a knob 36, and the driving gear 18 of the left hand pair of rollers being operated 55 by a knob 37.

The cabinet or housing is provided with a cover 38, similar to the cover 2 in Figures 1 and 2, but this cover is provided with three slots or sight openings 8A, one for each sheet, 60 as shown by dotted lines in Fig. 4.

In connection with the apparatus shown in Figures 4, 5 and 6 I employ three strips or sheets B, C and D each of which is connected at its ends respectively to a pair of rollers so as to be wound either forward or backward 70 to display the various words, or phrases thereon, together with their designating numbers and code letters, as will now be explained. The present system provides for the selective formation and combination of words, groups 75 of words and phrases one with another in practically unlimited number as may be necessary for the desired expression of a given phraseology, and thus eliminates the necessity of being limited in the expression of 80 thought to the stereotyped words, phrases and sentences shown in connection with a "topic" or "caption" word, as used in the ordinary telegraphic code books in present use, and permits of verbatim coding, as more fully described in another paragraph. 85

This system contemplates the forming of a designated phrase or sentence, by beginning with the initial word of each phrase, part of a phrase, or sentence, instead of reference to the 90 "topic" or "caption" word, and in order to accomplish this, the system operates as follows:

Each code strip or sheet B—C—D has displayed thereon in alphabetical order, commencing at the top thereof, vocabulary words, 95 phrases, or parts of phrases, letters, numerals, characters, or tables, et cetera, to the extreme left of which appear in numerical order, numbers commencing with 100, one number being assigned to each successive 100 line, and directly in line with the designated vocabulary words, phrases, et cetera. The result of this in each instance, is the indication of one line, said numerals being a necessary part of the system as a whole, though not necessary for the direct coding or decoding according to the particular system herein described. 105

The system of coding contemplates the employment of the letters comprising the 110 alphabet, in groups of two, three, four or five letters, arranged in proper alphabetical sequence peculiar to this system, which may be connected or combined with a similar alphabetical group or groups, for the convenient 115 and grammatical joining of two or more, words, phrases, parts of phrases, sentences or parts of sentences, such group letters, whether connected or not, comprising the code word or words necessary for the proper 120 communication of thought by telegram, cable or radio, as embraced in the present practice of telegraphic, cable and radio correspondence. In the system herein described, however, I employ groups of three-letter combinations, as shown in Fig. 4. 125

Adjacent to the left hand edge of code strip B, as stated above, is printed a column of numbers running from 100 to approximately 5,380 which number represents the number 130

of three-letter combinations obtainable by alphabetical combinations of the letters A—B—C—D—E—F—G, in three-letter groups, for example: AAA—AAB—AAC and on to 5 AZZ, then ABA, ABB, ABC and on to ABZ, followed by ACA, ACB, ACC, etcetera, until AZZ is reached, then the use of the combinations made possible by the initial letters B—C—D—E—F—G.

10 Adjoining the column of numbers on the code strip B is printed a column of three-letter groups of code combinations or artificial words of three letters commencing with AAA and continuing in the alphabetical sequence above mentioned, until the letter combination GZZ is reached, each letter group being in line with one of the above numbers.

15 Adjoining the column of code letter combinations, is a column of vocabulary words or phrases, et cetera, the initial words being arranged in alphabetical sequence and comprising verbs, adverbs, prepositions, pronouns, et cetera. The intention being to use code strip B principally for phrase combinations, this column begins with the word 20 "About", which word is used as the initial word of a great many phrases in ordinary communication, such as About a, About all, About any, About as, About as soon as, et 25 cetera. The system contemplates the use of as many grammatical combinations with the initial word "About" as are expressed in the communication of thought. The next word in alphabetical sequence is "Above" to which 30 is joined in similar phrase sequence, for example: Above a, Above all, Above any, et cetera; followed by the initial word After with various combinations, likewise Again, then All, Am, An, And, Are, As, At and so 35 on throughout the alphabet.

40 Code strips C and D are primarily used for individual words of the vocabulary used in common parlance in alphabetical order, such as Abandon—s, Abandoning; Abide—s. Abided, Abiding, Ability, Able, Ably, 45 Abolish, et cetera, interspersed, however, with phrases for the proper operation of the system such as Able to, Able to be, Able to do, et cetera and in like manner to the above description of code strip B, these strips C and D are provided with a column of numerals commencing with 100 and running up to approximately 5,380, with a column of code-letter groups beginning, for example with the 50 initial letters H—I—J—K—L—M—N—O—P—Q, on code strip C and R—S—T—U—V—W—X—Y—Z on code strip D and running through approximately as many three-letter combinations and in the same sequence,

55 60 as described in corresponding code strip B, each code word being in line with one of the numerals on the left and the vocabulary word or phrase on the right side of same.

The operation of coding a question or 55 statement in connection with the apparatus

shown in Fig. 4, is accomplished in the following manner: say for example, it is desired to code the statement:

"If you are not in position to do anything"

The person in charge first turns the left hand knob 37 to move the code strip B either forward or backward, as the case may be, until the group of words or phrases beginning with "If" is seen through the sight opening 8A in the cover, and the particular phrase 70 "If you are not" of this group is selected, and positioned directly above the lower edge of the sight opening, which enables it to be easily read, as all the matter below that particular line is shut out by the cover. The code-letter combination designating this phrase is AFP. The knob 35 is then turned to move the middle code strip C until the group of words or phrases beginning with "In" is 75 seen through the middle sight opening, and the phrase "In position" is selected, and brought to stand directly above the lower edge of the said sight opening, and in line with the selected phrase on code strip B. The code-letter combination designating this phrase 80 is "HER." The knob 36, is then turned to move the right hand code strip D until the group of words or phrases beginning with "To" is seen through the right hand sight opening, and the phrase "To do anything" is 85 selected and brought to stand directly above the lower edge of the said sight opening, and in line with the other selected phrases. The code-letter combination designating this phrase 90 is "RFT" the entire line of selected 95 code-letter combinations and phrases will then read as follows:

100 AFP—If you are not HER—In position RFT—To do anything and the combination artificial code word ready for transmission 105 will be AFPHERRFT.

110 It will thus be seen that with the use of only nine code letters, three different phrases are combined to make up the desired statement, and with the contemplated vocabulary, an almost endless number of words or phrase combinations is possible, thereby affording ample material for the verbatim expression of practically any desired statement, question, report, instructions, information, et 115 cetera, such as would be used in communications requiring code transmission. Attention is here called to the fact that reference to the ordinary codes in book form will show that only two phrases may be connected or combined by the employment of two five-letter code words or ten letters in combination.

120 In making up a message any desired word or phrase may be selected from any one column and combined with a word or phrase in any other column or columns, or the matter necessary may all be found in one column 125 it being understood that the selected words and phrases do not necessarily occur in con-

secutive order with respect to the several columns.

With the above arrangement this system provides for practically verbatim coding, and special attention is called to the elasticity afforded in the use of the vocabulary, wherein it is possible to use any word or phrase at the beginning of a phrase or sentence, in the body of same or at the end, for example:

10 Containing 10 Acres MORE OR LESS
It is MORE OR LESS a matter—
MORE OR LESS if this is—
We are not in position AT THIS TIME
AT THIS TIME of the year
I cannot come AT THIS TIME on account of

15 It will be noted from the above that the system obviates the necessity of the sender of a code being obliged to make extensive changes in the phraseology of his original text in order to conform to the ordinary phrases and words in book codes, but on 20 the other hand, as stated above, the same may be selected verbatim to meet his requirements.

25 In decoding, the operation is in reverse order to the operation of coding. For example, when a message in the form of a group of code letters of the three sheet system is received, the letters are taken up successively in groups of three letters each; the first 30 group is found by turning the strip until that group appears through the sight opening, and the word or phrase indicated by the code letters is written down. Then the next group or groups of code letters are found 35 in the same manner and the words or phrase indicated by these code letters are set down in order and the words and phrases thus found will constitute the translation of the message.

40 The line numerals above referred to as appearing on each code strip, aside from serving as line designation also permit this system to be used as a cipher code, wherein figures are used in combination instead of letters, attention is also called to the fact that this system contemplates in cases where an 45 absolutely private, confidential and secret code is desired for communication, that the code strips be printed in form as above described but without showing the three-letter 50 code combinations, in which event a private "key" may be prepared by using the three-letter code combinations in conjunction with the line numerals, thus the code strips containing the vocabulary and phrases are rendered meaningless and unintelligible to the 55 casual observer, in the same manner as though it were a speller or dictionary, thereby providing safe, certain and ample means for absolutely secret communication.

60 In the make-up of the code strips B—C—D, a great many words and phrases are employed, also "figures of speech" et cetera, which used singly or in combination with two 65 or more phrases, are designed to cover the

vast requirements of commercial, social and private communications, in fact wherever a code system is required.

While the foregoing described system contemplates its use for general every-day business and social parlance to an unlimited degree of phrase combination, yet it is also anticipated that there may not only be added to this system of code vocabulary, a vocabulary of technical terms and phrases, but also 75 the special terms and technical matter comprised of words and phrases germane to a particular line of business or industry, thereby combining in this system a means of unlimited possibilities so far as communication 80 by telegraph, cable or radio is concerned.

In the arrangement shown in Figures 1 and 2, a single code sheet or strip is used for displaying the numbers, code letters and vocabulary and therefore the housing is provided 85 with but a single pair of rollers, to which the respective ends of the said sheet are secured in the manner previously described.

The code sheet or strip is divided into five columns of words and phrases which constitute a vocabulary and which are arranged in alphabetical groups, as in the case of the three strip system, and adjoining each column of words and phrases on the left side is a column of single code letters, the letters of each column being indiscriminately arranged when 90 read from top to bottom but the letters of the several columns are alphabetically arranged when read from left to right.

95 Before and adjoining the first column of single code letters, is a column of double code letters which are arranged in groups, such as a group of the combination AA followed by a group of the combination AB, and so on and adjoining the column of double letters is 100 a column of numbers beginning with 100 and continuing in regular order to the last letter combination in the adjoining column; thus each horizontal line of words and phrases from the vocabulary is designated by a number.

105 By arranging the double code letter combinations in groups as above described, the same double letter combination would indicate all the words or word and phrase combinations 110 used in that group in the first column, but the single code letter would be different for each line in the group.

115 The words and phrases constituting the vocabulary, are arranged in alphabetical groups in the several columns; all the phrases of each group beginning with the same initial word, as in the case of the three sheet system hereinbefore described. For example 120 there would be a group in which the initial word of each phrase would be "About" another group having the initial word "Above" followed in order by "After" and "Again" 125 and so on for as many of these groups of 130

phrases, as would meet the requirements contemplated in this system.

In coding a sentence, or statement or question in connection with the single-strip system, the operation is as follows: For example, in order to code the question "Do you favor acceptance", the knob 19 is turned to move the strip either forward or backward, as the case may be, until the group of phrases beginning with "Do" is seen through the sight opening 8, this group occurring in the second column and the words "Do you" of this group are selected and positioned immediately above the lower edge of the sight opening in order to be clearly distinguishable.

The code letter immediately preceding these words is "V" and the double letter combination in line with these words is "AB". The knob is again turned to shift the strip until the group of words or phrases beginning with the letter "F" is found this letter occurring in the fifth column, and the word "Favor" is selected.

The code word immediately preceding this word is "E" and the double letter combination in line with this word is AA. The next word "Acceptance" will be found in the fourth column; the code letter immediately preceding the same is "K" and the double letter combination in line therewith is "AA."

Thus the question "Do you favor acceptance" is coded as follows: ABV—Do you AAE—Favor ABK—Acceptance. It will be noted that the above example, all of the words or phrases making up the question are visible at one time and this particular question was chosen in order that the manner of selecting the various words or phrases making up the question, might be seen at a glance. In cases where the code strip must be shifted back and forth in order to select the words or phrases necessary to make up a given message, the pointer 22 may be moved to indicate the code letter for each selected word or phrase, thereby to avoid confusion or mistake, and note is made of each word or phrase and its indicating code letter.

The vocabulary also contemplates the use of figures, words, phrases and characters for expressing the various money systems, tables of weights and measures, numerals, specifications, fractions, decimals, time, dates, companies and other miscellaneous matter together with the necessary code letters, for example:

9124 Tons
83 POUNDS 7 OUNCES
10,987,456

and so on for the coding of any character of miscellaneous matter, and this matter is arranged in columns and each line is provided by a code letter group and a number,

in the manner hereinbefore described, the columns of miscellaneous matter following immediately after the columns of words and phrases making up the general vocabulary. In coding this miscellaneous matter, in connection with the three-strip system it will be seen that by shifting the strips, figures and numbers can be combined to form any larger number; also that combinations of numbers and words or phrases can be made for the expression of any information contemplated in the vocabulary.

Having described my invention what I claim as new and desire to secure by Letters Patent is:

1. Apparatus for coding and decoding comprising a plurality of parallel and longitudinally shiftable code strips, each of said code strips having a plurality of transversely disposed lines of words and phrases arranged thereon in alphabetical groups and code designations preceding each line.

2. In a coding apparatus of the character described, a plurality of parallel and independently shiftable code strips having a plurality of lines of words and phrases thereon arranged in alphabetical groups, and a code-letter combination preceding each line the letters in each combination corresponding in number to the number of code strips.

3. In a coding apparatus of the character described, a plurality of parallel and independently shiftable code strips each having a plurality of lines of words and phrases thereon arranged in alphabetical groups and a code letter combination preceding each line of each group, the code letter combinations on each strip being arranged in alphabetical sequence when taken in successive order and the number of letters in each combination corresponding to the number of strips.

4. In a coding apparatus of the character described, a plurality of parallel and independently shiftable code strips each having a plurality of lines of words and phrases thereon arranged in alphabetical groups, the phrases of each group having a common initial word, and code letters preceding each line.

5. In a coding apparatus of the character described, a plurality of parallel and independently shiftable code strips each having a plurality of lines of words and phrases thereon arranged in alphabetical groups, the phrases of each group having a common initial word, code letters preceding each line, and a number preceding each combination of code letters.

6. In a coding and decoding apparatus, a plurality of vertically arranged and vertically shiftable code strips, each of said code strips having arranged in horizontal lines thereon significant descriptive matter and code designations preceding the same, the descriptive matter on the several strips being

of such respective natures that a complete message may be formed by placing lines of descriptive matter on the several strips in horizontal alinement.

- 5 7. In a coding apparatus of the character described, the combination with pairs of rollers; of code strips each of which is secured at its ends to a pair of said rollers, each of said strips having lines of words and 10 phrases thereon arranged in alphabetical groups and in column formation, and code letters preceding each line which are arranged in alphabetical sequence when read downward from the top of the strip and separate mechanism for turning the rollers of 15 each pair simultaneously and in the same direction, to bring a required line on any strip into view and to position the individual lines on the same horizontal line.
- 20 8. In a coding apparatus of the character described, the combination with independent code strips each having a plurality of lines of words and phrases thereon and code letters preceding each line; of a housing, independent pairs of rollers in said housing, 25 each of said strips being secured at its ends to a pair of said rollers; a cover for said housing having sight openings therein, and independent mechanisms for turning the rollers of each pair simultaneously and in the same direction to bring a desired line on any strip into view.
- 20 9. In a coding apparatus of the character described, the combination with independent code strips, each having a plurality of lines of words and phrases thereon arranged in alphabetical groups, and code letters preceding each line on each strip, of a housing, independent pairs of rollers in said housing, 35 each of said strips being secured at its ends to a pair of said rollers, independent mechanism for turning the rollers of each pair simultaneously and in the same direction thereby to position required phrases on the several sheets on the same horizontal line, and a removable cover for said housing having sight openings therein.

In testimony whereof I affix my signature.
HARRY R. BARNETT.
